UNITED STATES PATENT OFFICE.

JOSEPH P. McCARTHY, OF UTICA, NEW YORK, ASSIGNOR OF ONE-THIRD TO WILLIAM CLEVELAND AND ONE-THIRD TO PETER SAWICK, BOTH OF UTICA, NEW YORK.

PISTON-RING TOOL.

Application filed May 15, 1926. Serial No. 109,369.

This invention relates to new and useful improvements in piston ring tools, and has for one of its objects the provision of a tool which is particularly adapted for use in placing piston rings in the piston and the entirety in the cylinder.

Another object of the invention is to provide a tool which is in the form of a sleeve for surrounding the piston ring or rings, the lower end of the sleeve being formed with an upwardly and outwardly beveled portion whereby the sleeve will fit within the beveled upper end of the cylinder and thereby insure the passing of the piston with the rings attached thereto into the cylinder.

Another object of the invention is to provide a sleeve for the purpose set forth which is constructed with a plurality of longitudinally disposed sections having their upper ends secured by links to a ring of larger diameter, whereby said sections may be readily positioned in close contact with the wall of the piston throughout the lengths of said sections, to thereby cause the links to be properly compressed within the channels of the piston ring while the entirety is being positioned within the bore of the cylinder.

A still further object of the invention lies in the provision of a sleeve of the type described in which an expansible member is associated with the lower ends of the sections so as to permit the sleeve to be readily adapted to cylinders of different diameters.

Another object of the invention is to provide a piston ring tool of the character described in which the expansible member is constructed with means for varying its expansibility, whereby the tool may be readily adapted for pistons of extreme diameters.

With the foregoing and other objects and advantages in view as will be evident from the subsequent description, the invention consists in the construction and arrangement of the several parts as will be more fully hereinafter described and claimed.

In the accompanying drawings:

Figure 1 is a vertical sectional view of a cylinder and piston and showing the application of my invention thereto;

Fig. 2 is an enlarged top plan view of my invention;

Fig. 3 is a detail plan view, the sections of the sleeve being shown in section, the view showing particularly the connection between the ends of the expansible coiled spring, and

Fig. 4 is an enlarged detail sectional view through the spring, showing the means for varying its expansibility.

Like reference numerals designate corresponding parts throughout the several figures of the drawing.

In the drawings I have illustrated a cylinder 5 having a bore 6, the upper end thereof being formed with the usual beveled end 7, and a piston 8, which is adapted to slide within said bore. The piston is provided with a plurality of grooves 9 for receiving the split piston rings 10.

In order to easily position and retain the rings 10 in the grooves 9 while the piston is being inserted within the bore 6, I have provided a sleeve A which is radially adjustable to fit against the periphery of the piston. This sleeve comprises a ring 11, a plurality of longitudinally extending sections 12, and a plurality of links 13, the latter respectively connecting the sections 12 with the ring 11. The lower ends of the sections 12 are respectively outwardly and upwardly inclined to fit within the bevel 7 of the cylinder bore, and to this end the lower end of each section 12 is sharply bent upwardly and outwardly, as indicated at 14, the upturned portions of said sections being thence curved upwardly and inwardly to form seats 15. Disposed within the seats 15 is an expansible member B which in this instance is formed from a single length of coiled spring, the ends thereof being formed into inter-engaging hooks 16 and 17, respectively. The length of the spring is such as to cause the sections 12 of the sleeve A to properly fit a standard size cylinder. It may be desirable to employ the improved tool on a cylinder of lesser diameter, and to this end I have provided a take-up means in the coiled spring whereby its expansibility may be varied. For this purpose I have provided a take-up member within one end of the spring. This take-up member, as specifically illustrated, consists of a V-shaped link 18 having its ends 19—19 looped about a convolution of the spring at a point some distance from the end of said spring. A second link 20 is pivotally connected to the apex of the V-shaped link and the outer end of this link 20 projects beyond the adjacent end of the spring and is formed with an eye 21, which is adapted for engagement with the hook 16 whenever it is desired to reduce the

expansibility of said coil. It will also be noted that by reducing the expansibility of this coil, a greater tension is thereby created. It will be further observed that after the rings have been inserted in the grooves and the sleeve positioned around the rings, a downward movement on the ring 11 will force the sections 12 of the sleeve A inwardly towards the piston and thereby firmly compress the piston rings within their respective grooves and hold said piston rings in said grooves while the piston is being inserted within the bore of the cylinder.

It will be obvious that changes in the proportions and dimensions of the several parts may be adopted without departing from the spirit or scope of the invention as set forth in the appended claims.

I claim:

1. In a piston ring tool, the combination of a sleeve formed by a ring and a plurality of longitudinally extending sections pivoted at their upper ends to said ring, the lower ends of said sections being outwardly and upwardly inclined to fit within the beveled upper end of the cylinder bore and expansible means surrounding the sections directly above said upwardly inclined lower ends.

2. In a piston ring tool, the combination of a sleeve formed by a ring, a plurality of links pivotally connected to said ring, a plurality of longitudinally extending sections respectively pivoted at their upper ends to said links, and expansible means surrounding the lower ends of said sections.

3. In a piston ring tool, the combination of a sleeve formed by a ring, a plurality of links pivotally connected to said ring, a plurality of longitudinally extending sections respectively pivoted at their upper ends to said links, the lower ends of said sections being outwardly and upwardly inclined to fit within the beveled upper end of the cylinder bore, and expansible means surrounding the lower ends of said sections.

4. In a piston ring tool, the combination of a sleeve formed by a ring and a plurality

of longitudinally extending sections pivoted at their upper ends to said ring, the lower ends of said sections being sharply bent upwardly and outwardly to respectively form beveled lower ends to fit within the beveled upper end of the cylinder bore.

5. In a piston ring tool, the combination of a sleeve formed by a ring and a plurality of longitudinally extending sections pivoted at their upper ends to said ring, the lower ends of said sections being sharply bent upwardly and outwardly to respectively form beveled lower ends to fit within the beveled upper end of the cylinder bore, the upturned portions of said sections being curved upwardly and inwardly to form seats, and an endless coil spring fitted within said seats.

6. In a piston ring tool, the combination of a sleeve formed by a ring and a plurality of longitudinally extending sections pivoted at their upper ends to said ring, and an expansible ring surrounding the lower ends of said sections, said ring being formed from a coil spring having interengaging hooks at its ends, and a take-up member disposed within the coil, one end thereof being connected to the coil at a point removed from one end thereof and having an eye projecting from said end for engagement with the hook of the opposite end of the coil.

7. In a piston ring tool, the combination of a sleeve formed by a ring and a plurality of longitudinally extending sections pivoted at their upper ends to said ring, and an expansible ring surrounding the lower ends of said sections, said ring being formed from a coil spring having interengaging hooks at its ends, and a take-up member disposed within the coil, and comprising a link having one end connected to the coil at a point removed from one end thereof, and a hook pivoted at its inner end to said link and adapted for engagement with the hook of the opposite end of the coil.

In testimony whereof I hereunto affix my signature.

JOSEPH P. McCARTHY.
